UNITED STATES PATENT OFFICE.

MARDSEN C. HUTTO, OF DETROIT, MICHIGAN.

METHOD OF MANUFACTURE OF ABRASIVE DEVICES.

Application filed June 18, 1926. Serial No. 116,835.

This invention relates to an improved method of manufacture of abrasive devices of various types, such as grinding stones for use in internal grinders or grinding wheels and various other types of manufactured abrasive devices formed of a composition of material including an abrasive and a binder commonly in use.

The purpose of the invention is to provide a method of manufacture whereby the finished abrasive device is of practically uniform hardness throughout. With abrasive devices as usually made the material is not of uniform hardness resulting in soft spots whereby the stones will wear more rapidly at one point than another and require continual dressing to secure the necessary uniform surface shape. I have discovered that this softness occurs in the usual manufactured article as heretofore made by reason of the material not being compacted to an equal degree so that, when it is submitted to pressure in the mold or form provided therefor, the portions of less compactness are not submitted to the same pressure as those portions that are more compact. This inequality in the hardness of the stones of various forms has previously been attributed mainly to non-uniformity of the mixture. I have discovered that this is in error and the non-uniformity in the hardness and wearing quality of the stone is produced directly by reason of inequality in the compactness of the material before submission to pressure in the mold.

Abrasive devices of the character herein described are usually formed of an abrasive material as for instance silicon carbide and a binder and additional chemical constituents including a small percentage of moisture. This material is well known in the art and the actual constituents of the stone are not involved in this invention. This material is in a ground form and the fineness depends upon the quality or texture of the stone to be produced and ordinarily is placed in a mold and subjected to the necessary pressure and then is fired in a kiln similar to a ceramic kiln. I have found that, in placing of the material in a mold the workman in resting his hands upon some portion of it or in some other way will compact the material at some point or points to a degree greater than at some other portion of the surface which results in the stone having soft and hard spots as above mentioned. My process seeks to ob-

viate this difficulty enabling the workman to place material in the mold as usual and in which some portions may be compacted to a degree greater than others and still produce a stone that is of uniform hardness. In the carrying out of this process some means is required to submit the entire area of the material to an equal pressure and the accompanying drawings are illustrative of a machine adapted to perform this function.

Such a machine is shown in the accompanying drawings in which—

Fig. 1 is a front elevation thereof.

Fig. 2 is a side elevation.

Fig. 3 is a view of the form in which the material is compacted.

It is to be understood that any mechanism or means by which the material may be compacted uniformly previous to submission to pressure may be utilized. The drawing merely illustrates a hand-operated device used in the performance of this step of the process. This machine consists of a main frame 1 having the two uprights 2 and 3 and cross member 4 at the top apertured to receive the tamping bars 5. Adjacent the lower or tamping end of these bars, each is provided with an elongated slot 6 in which is positioned a rod 7 extending across the machine, the uprights 2 and 3 being apertured to permit the rod to extend therethrough. This rod is supported adjacent each side frame by a pivoted arm 8, 8. A coiled spring 29 connected with each arm tends to raise the rod and therefore to lift the tamping bars upon the rod engaging the upper end of the slot. These bars lie in alignment in the machine here shown which is adapted to produce a comparatively narrow rectangular stone with the mold illustrated. The mold may be of any particular character here shown as being formed of two end members 9 and 10 and the longitudinal connecting members 11 and 12 spaced apart at the center as shown. In this central space 13 is provided a loose die block 14.

The mold is designed to be positioned on two gauge bars 15 and 16 which lift the mold relative to the die block and determines the thickness of the stone—that is, if a stone of greater or less thickness than is indicated by the drawing is desired, gauge bars of greater or less thickness are provided to position the mold relative to the die block. This block 14 is comparatively loose in the slot or space 13 and rests upon the same foundation as the

105

110

bars 15 and 16. On the upper surface of this mold I provide a small hopper indicated generally at 17 formed of two parts hinged as shown clamped together at one end by 5 means of a screw clamp 18. The mold is positioned between the side members of the frame and directly beneath the ends of the tamping bars after being filled with the granular material by hand or in any ap- 10 proved manner. By pressing downward on the rod 7 the bars are allowed to move downwardly by gravity and the slot in the bars is sufficiently long to enable the rod to be re- tracted from contact with the upper side 15 thereof so that each bar rests freely and by gravity upon the material in the mold. These bars are exactly alike in weight either being formed in a mold or subsequently machined or otherwise finished in such manner 20 that they are practically exactly equal in weight. In the machine shown the bars are spaced apart a distance equal to their width longitudinally of the mold and in the use of this machine the tamping bars are first low- 25 ered to position on the filled mold and hopper so that each of the points contacted by a tamping bar is subjected to equal pressure and the tamping bars are then lifted and the mold box (which is less in length than the dis- 30 tance between the side bars 2 and 3 of the machine) is moved endwise so that the spaces between the bars not tamped in the first operation are brought to registration with the ends of the tamping bars which are again lowered 35 onto the material in the mold. Thus, the entire surface of the material is subjected to exactly equal pressure and the body of material in the mold and hopper is compacted uniformly. The machine shown is adapted 40 to make a single stone but the process contem- plates the use of any number of tamping bars and any shape of mold. The machine will correspondingly differ in the arrangement of its parts while the function thereof remains 45 the same. The mold box in the machine shown is limited in its movement by means of screws 19 and 20 in the respective side members of the frame so that in placing the mold in position in contact with one screw 50 at one end or the other the proper registration of the mold and tamping bars is secured but any arrangement of mold and frame to secure the desired registration with the tamping bars to insure each small area being 55 tamped may be used. It is to be noted that this mold and hopper may be filled in any ordinary way as by hand and in the performance of the process it is not at all im- portant as to whether or not some portions 60 of the material are pressed into the mold with greater pressure than some other parts unless the pressure be excessive or in ex- cess of the weight of the individual tamping bars which would be quite unusual and would 65 require a definite action on the part of the workman to secure such a result. Ordinarily in the mere filling of the mold by hand even though some portions of the material are pressed to a degree greater than some of the parts the lowering of the tamping bars to the 70 position so that the weight of the same is caused to exert pressure upon the surface practically throughout its whole area, those points or spots of material in the mold that are naturally of less compactness than others 75 will be brought to the same degree of compactness by the pressure of the tamping bars. The result usually is that the bars at the end of the mold are moved downwardly to an extent greater than those at the center of 80 the mold as is suggested in Fig. 3, and that the surface of the material after being compacted by the tamping bars still lies above the upper surface of the die block and in the hop- 85 per. Subsequent to the tamping operation the hopper is removed, it being merely re- tained by dowel pins one of which is indi- cated at 21 on the surface of the mold. After removal of the hopper the mold is struck off at the upper surface leaving it filled with 90 material of equal compactness throughout its area. This mold after being struck off, as stated, is placed in any convenient machine, as a press and the material in the mold com- pressed to the required degree to produce the 95 desired hardness of the stone. It is to be un- derstood that the pressure to which the molded material is subjected after being first compacted, as stated, depends very largely upon the character of the stone to be manu- 100 factured—that is, if a stone of extreme hard- ness is desired it is submitted to a greater pressure and if less hardness is desired corre- spondingly less pressure is utilized. After 105 being submitted to the final pressure as stated, the stone is fired in a kiln in the usual way and subsequently utilized for the purpose for which it is designed.

The essential feature of the process is in the step of first compacting the material to 110 an equal degree over its entire area previous to submitting to the pressure by which the final hardness of the stone is largely deter- 115 mined. This process so far as my knowledge extends, has never been utilized in the manu- 120 facture of an abrasive device of any type and by such step the finished abrasive device has no so called "soft" spots and therefore will wear economically in use without particular deformation of the surface and the extent to 125 which the surface of the stone requires dress- 130 ing after use is reduced to a minimum. Also by this process I am able to assure buyers of practically absolute uniformity in the hard- ness of the abrasive devices, and that this quality is uniform throughout the entire stone which may be worn to its limit of wear without any change in its uniformity. I am therefore able to provide an abrasive device with a much longer life than has heretofore 130

been possible, that has the uniformity of hardness so greatly desired by users that to a very material extent reduces the dressing of the device to a minimum during its period of use to maintain a uniform surface shape. 5 One of the difficulties at present encountered in this art is that grinding stones or wheels are designated by a grade known to vary greatly in their hardness, although they may 10 have been submitted to a pressure over the whole surface that determines the grade. This inequality in grade arises as before stated by reason of the fact that the material, before being subjected to the pressure determining its final hardness, is not uniformly compacted. This process therefore eliminates waste both in use and in manufacture and there is no loss of stones in manufacture due to imperfection as to grade hardness as 15 20 is the case under methods at present in use.

The process, as above described, contemplates the manufacture of an abrasive device which requires to be fired in a kiln but there are abrasive devices that do not require final 25 firing and this process is of equal value in the formation of the articles of this type for the reason that uniform hardness of wearing surface and uniform hardness of the body is as desirable as in that class of articles which require the final step of firing. Thus, the process 30 is adaptable for use with various articles formed of a granular material and is adapted for use in compacting granular material not of an abrasive character but in which uniformity in compactness is a necessary feature, and experience has established that this 35 uniformity of compactness of the article of whatever character formed of a granular material is in the step of first subjecting it while 40 in a mold form to an equal light degree of pressure throughout small areas whose total equals the total area of the article and then subjecting this lightly compacted material to a greater pressure. The method at present in 45 use in various articles formed of granular material contemplates the subjecting of the whole area at one stroke or at one time to pressure. This method now in use is inadequate due to the fact that the parts of material more highly compacted in the placing in 50 the mold prevent the plunger or means used to exert pressure thereon to exert its pressure uniformly. By using a plunger formed of a large number of small parts each acting independently of the other the whole surface 55 may be compacted at one time and to an equal degree after the general manner described.

Having thus fully described my process, what I claim and desire to secure by Letters 60 Patent of the United States is—

1. The method of manufacture of an abrasive device from granular material of the desired composition which consists in first filling a mold with the material, then tamping 65 small areas of the material individually to a

substantially equal degree of pressure, striking off the mold, submitting the molded material to a greater degree of pressure, and finally firing the molded article.

2. The method of manufacture of abrasive devices of ground material of the desired fineness and composition consisting in first filling a mold with material, then subjecting the same to pressure in independent small areas over the entire surface so that the entire area has been compacted to an equal degree, then submitting the compacted article in the mold to a higher pressure, and then firing the article thus formed.

3. The method of manufacture of abrasive devices from granular material of the desired fineness and composition, the step consisting in submitting small areas of the material to an equal pressure, the total of the small areas being equivalent to the surface area of the device, and then submitting the entire area to a higher pressure to produce the final desired compactness, and then firing the article.

4. The method of forming an abrasive device from granular material of the desired character and composition which consists in placing the same in the mold, compacting the material in the said mold to a slight degree of pressure in such manner that the material is compacted to substantially equal degree throughout the body thereof, then submitting the compacted material to a high degree of pressure uniformly over its surface, and finally firing the formed article.

5. The method of forming an abrasive device which consists in preparation of the material in a granular form of the desired fineness and composition, placing the same in a mold of separable parts having a depth greater than the desired thickness of the finished article, subjecting the surface of the material while in the mold to equal pressure throughout small areas thereof in such manner that the entire surface area of the material has been subjected to an equal pressure and the material in the mold is of substantially equal compactness throughout the entire body, then separating the mold by removal of the upper portion and striking off the material to the surface of the remainder of the mold and then subjecting the material in the mold to a higher degree of pressure to produce a body of the desired hardness and of equal compactness throughout its area and finally firing the said formed article.

6. The method of making an abrasive such as a grinding stone, wheel or similar article, the steps consisting in the filling of a mold with material of the desired fineness and composition and to a depth greater than the final thickness of the article, then subjecting the material to comparatively light pressure through comparatively small areas so that the entire surface is subjected at said areas to an

- equal degree of pressure and the material in the mold compacted to an equal degree throughout its body, then cutting off the upper surface of the compacted material so that the material remaining in the mold is of uniform depth, then subjecting the compacted material to a higher degree of pressure. 5
7. In a method of preparing granular material to form an article of equal hardness throughout its body which consists in placing the material of the desired composition in a mold, the depth of which is greater than the thickness of the article to be formed, then compacting the material in the mold by subjecting the surface thereof at a plurality of small areas equaling approximately the area of the article to be formed to a slight degree of pressure so that the material is first compacted to a slight degree to an equal extent 10 throughout the entire body, removing the upper portion of the compacted material to provide a level upper surface, and then subjecting this material over the entire exposed surface in the mold to a materially higher
- degree of pressure whereby the molded article is of uniform hardness. 25
8. The herein described method of manufacturing an abrasive device from granular material which consists in filling a mold with the material, then tamping small areas of this material individually under substantially equal degrees of pressure, then striking off the mold, and then submitting the material in the mold to a greater degree of pressure. 30
- 9: The herein described method of producing an abrasive device from granular material which consists in filling a mold with the material, then tamping small areas of this material individually by means of tamping members which are adapted to press by their weight only against the granular material, then striking off the granular material in the mold, and then submitting the remaining material in the mold to a greater degree of pressure. 35

In testimony whereof I sign this specification.
